AUTOMATIC FIRE EXTINGUISHING APPARATUS.

No. 406,088.

Patented July 2, 1889.

UNITED STATES PATENT OFFICE.

JOSEPH CLAPP, OF EVANSTON, ASSIGNOR TO THE CLAPP AUTOMATIC FIRE-EXTINGUISHER COMPANY, OF CHICAGO, ILLINOIS.

AUTOMATIC FIRE-EXTINGUISHING APPARATUS.

SPECIFICATION forming part of Letters Patent No. 406,088, dated July 2, 1889.

Application filed September 1, 1888. Renewed May 17, 1889. Serial No. 311,167. (No model.)

To all whom it may concern:

Be it known that I, JOSEPH CLAPP, of Evanston, in the county of Cook and State of Illinois, have invented certain new and useful 5 Improvements in Automatic Fire-Extinguishing Apparatus, of which the following is a description, reference being had to the accompanying drawings, forming a part of this specification, in which—

10 Figure 1 is a vertical sectional view of a portion of a building supplied with a stand-pipe and water-distributing pipes, showing my invention applied thereto, the various parts being in their respective normal positions. Fig. 2 is an enlarged detail view, partly 15 in section, of the principal features of my invention, showing the operative parts in their respective normal positions. Fig. 3 is a like view showing said parts, respectively, in their 20 abnormal positions. Fig. 4 is a detail view, partly in section, of a three-way valve, showing the same in its normal position. Fig. 5 is a vertical sectional view of a building, showing a modification of my invention. Fig. 25 6 is a sectional view in detail of a portion of a pipe with a valve therein; and Fig. 7 is a detail view showing a modification of the shut-off valve.

Like letters of reference indicate like parts 30 in the different figures.

In the extinguishment of fires in factories and other buildings supplied with the usual distributing-pipes and automatic sprinklers the objection has been found in practice that 35 great damage has frequently been done to goods and stock, for the reason that the water often continues to flow long after the fire is extinguished.

The object of my invention is to overcome 40 this objection and to provide means for cutting off the flow of water upon any given floor or portion of a building, or upon all the floors, if there are more than one, and at the same time to sound an alarm to indicate that 45 said water is thus turned off, so that as soon as the sprinklers which have opened have been repaired or replaced by new ones the apparatus may be readjusted so as to cause the water to re-enter and traverse the pipes as before upon 50 the reopening of one or more of the sprinklers.

A further object is to so construct said mechanism that the water cannot be shut off from the distributing-pipes without causing an alarm to be sounded, thereby preventing unauthorized persons from tampering with said mechanism for unlawful purposes. 55

To this end my invention consists in the combination of elements hereinafter more particularly described and claimed. 60

Referring to the drawings, A represents the wall of a building, of which B indicates the floors.

C is the usual stand-pipe, connected with a source of water-supply, such as a tank above 65 or a pump beneath, or both.

D indicates the distributing-pipes, which are provided with automatic sprinklers D', which are held normally closed by means of fusible solder in any well-known way. 70

In the lower part of the building—as, for example, the engine-room—I place an air-reservoir E, which is supplied with compressed air by means of an air-pump E' connected therewith. Communicating with said reservoir is a pipe E², which is by preference carried upward, near to and parallel with the stand-pipe C. In each of the distributing-pipes, near to the stand-pipe, I place a valve F. The valve-seat f is shown in section in 80 Figs. 2 and 3. Said valve is normally open and is connected with a valve-stem f', which in turn is attached to a flexible diaphragm G, inclosed in a case or frame G', the whole of said parts serving to form a shut-off valve of 85 differential area, and the valve F may be generally understood as including them. The bottom of said case is connected by means of a pipe G² to the pipe E², or to an intermediate pipe, as hereinafter stated, if it is desirable 90 to shut off the water from more than one floor at the same time. Interposed in the pipe G² is a valve H, having a handle H' upon the outside for rotating the valve-plug H², the normal positions of said handle and plug being as shown in Figs. 2 and 4, so that the air from the reservoir is prevented from passing upwardly to the diaphragm G, while any air which may be contained in the pipe G² between the diaphragm G and valve H is free 95 to escape through the way h, Figs. 2 and 4, when the valve H is in its normal position. 100

In Figs. 2 to 4, inclusive, I have indicated a three-way valve for controlling the flow of air in the pipe, in which case it is necessary to form an opening h' in the shell of the 5 valve opposite the way h , when in its normal position, as shown in Figs. 2 and 4; but a simple stop-cock may be utilized with equal advantage, provided a separate escape is made for the air from the diaphragm G when it is 10 desirable to open the valve F . When there is more than one floor or more than one set of distributing-pipes, I prefer to employ a separate escape for the air, as stated, in which event the three-way valve may be dispensed 15 with, as hereinafter set forth.

J represents a box or case located near the valve H and provided with a door J' and a suitable lock for fastening the same. Within said case I place a windlass J^2 , to 20 which is attached a weight and cord $j j'$, which, when wound up, is held normally in that position by means of a ratchet J^3 and pawl j^2 . Said pawl is attached by means of a rod j^3 to the handle H' of the valve H . A 25 pivoted arm j^4 is arranged in the case with its free end bearing upon a square portion of the windlass J^2 , and is in turn connected by means of a rod to a pivoted bell-hammer j^5 , arranged in proximity to a bell J^4 . Upon 30 turning the arm H' to an abnormal position, as indicated in dotted lines in Fig. 3, the pawl is released from the ratchet and the weight falls, thereby ringing the alarm and indicating by its position that said valve has 35 been opened. Upon turning the valve H , as described, the compressed air from the reservoir E acts upon the diaphragm-valve G , which in turn closes the valve in the distributing-pipe, with the stem of which it is connected. It will be observed that this valve 40 cannot be closed except by admitting the air thereto, which is dependent upon the opening of the valve H . This cannot be accomplished except by sounding the alarm in the box J , which operates as a check against closing the valve F by unauthorized persons, and as the alarm is protected by lock and key it is also prevented from thus being interfered with. If there is more than one 45 floor, I prefer to have such alarm-box upon each as well as in the office or engine-room; but a single one in the office or engine-room may serve all purposes. In Figs. 1 and 5 I have shown such a one so located, the pawl j^2 50 of which is actuated by means of a diaphragm-valve K , the stem k of which is attached to said pawl, as shown. Said diaphragm-valve is connected with the valve H by means of a pipe K' , so that the air from the reservoir 55 may be admitted to said diaphragm either directly through the three-way valve, or as shown in Fig. 5, hereinafter described.

L , Figs. 1 and 5, indicates a pressure-regulator connected with the reservoir to indicate 60 the degree of air-pressure therein.

In Fig. 1 the valve H , as stated, is shown

upon the floor upon which the distributing-pipe is located.

In Fig. 5 I have shown my invention as applied to a number of distributing-pipes located upon different floors. It is obvious that in this event the air should be permitted to escape from the diaphragm-valves from but one point, and the three-way valves would permit the air to escape when not desired. I 70 therefore prefer to provide a separate pipe E^3 , parallel with the pipe E^2 , and to connect the pipes G^2 therewith. Stop-cocks H , normally closed, are then located in pipes E^4 , which connect the pipes $E^2 E^3$. In the pipe 80 K' , which communicates with the bottom of the pipe E^3 , and preferably within the case J , is located an escape-valve K^2 , which is normally closed. Upon opening any one of the valves H the air is admitted to the pipe E^3 , 85 through which it passes up and down into the several pipes G^2 , thus closing all the valves F connected therewith. Simultaneously it actuates the diaphragm K and sounds the alarm in the office. Upon replacing the 90 sprinklers after the fire is extinguished and closing the valve H that has been opened the air from the diaphragms G and K is permitted to escape through the valve K^2 , when the weight is wound up and the case locked, thus 95 leaving the apparatus in its normal condition and ready to shut off the water in the distributing-pipes and to sound an alarm whenever any one of the valves H is closed, whether there be a fire in the building or not. 100

I have shown a diaphragm-valve of differential area as the preferable construction for shutting off the flow of water to the distributing-pipes; but it is obvious that the pipes G^2 may be connected with cylinders in lieu 105 of the cases C' , in each of which may be inserted a piston attached to the valve-stem f , the whole forming a shut-off valve of differential area, as shown in Fig. 7. I do not confine myself, therefore, to either form, as I 110 regard one as the mechanical equivalent of the other, my object being to employ a shut-off valve of differential area to be closed by means of compressed air acting upon the larger surface. 115

The advantages of said invention are that it renders it possible to shut off the flow of water from the distributing-pipes of a building as soon as a fire therein is extinguished, thus avoiding damage by unnecessary flooding, while it is possible for those in charge of the building to know the condition of the shut-off valves through the alarm mechanism.

Having thus described my invention, I claim—

1. The combination, with the distributing-pipes of a fire-extinguishing apparatus of the class described, of one or more valves of differential area for shutting off the flow of water to the distributing-pipes, a source of compressed air connected therewith by a suitable pipe or pipes, and one or more valves nor-

mally closed for admitting said compressed air thereto, substantially as shown and described.

2. The combination, with the distributing-pipes of a fire-extinguishing apparatus of the class described, of one or more valves of differential area for shutting off the flow of water to the distributing-pipes, a source of compressed air connected therewith by a suitable 10 pipe or pipes, one or more valves normally closed for admitting said compressed air thereto, and means, as an escape-valve, for permitting the escape of air from the shut-off valves when it is desirable to open the same, 15 substantially as shown and described.

3. The combination, with the distributing-pipes of a fire-extinguishing apparatus of the class described, of one or more valves of differential area for shutting off the flow of water to the distributing-pipes, a source of compressed air connected therewith by a suitable 20 pipe or pipes, one or more valves normally closed for admitting said compressed air thereto, means for permitting the escape 25 thereof from said shut-off valve when it is desired to open the same, and an alarm mech-

anism in operative connection with said valve or valves by which the flow of air is regulated, substantially as shown and described.

4. The combination, with the distributing-pipes of an automatic fire-extinguishing system, of one or more normally-open differential valves for shutting off the flow of water to the distributing-pipes, a source of compressed air, a pipe or pipes for conducting the same to said differential valves, normally-closed shut-off valves located in said pipe and in operative communication with an automatic alarm mechanism, and means, as described, for inclosing and locking said alarm mechanism, whereby the opening of said shut-off valve may close said differential valves and sound an alarm by means of a mechanism protected from unauthorized interference, substantially as specified. 30 35 40 45

In testimony whereof I have signed this specification, in the presence of two subscribing witnesses, this 8th day of January, 1888.

JOSEPH CLAPP.
